PNEUMATIC SOUND PRODUCING DEVICE

William C. Eaves, Elyria, Ohio, assignor to Eaves
Sound Projectors, Inc., New York, N. Y., a cor-
poration of Delaware

Application September 2, 1942, Serial No. 457,057

9 Claims. (Cl. 179—108)

1

This invention relates to sound producing apparatus of the type wherein a stream of compressible fluid, such as air, is modulated to generate sound waves.

One of the objects of the invention is to provide a sound head of the fluid flow type embodying a novel balanced modulating valve.

Another object is to provide novel means for balancing the modulating valve of a sound head and for transmitting the balancing force to the movable member of the valve which means permit ready adjustment of the operative equilibrium position of the valve and add substantially no weight to the parts vibrating at the audio frequency of said valve.

A further object is to provide a novel air head which is so constructed that condensate or other moisture which tends to collect in the vicinity of the modulating valve will drain away, the drain passage or passages being so disposed and arranged as not to interfere with the volume and quality of the sound reproduction.

A still further object is to provide novel means for mounting the movable member of a modulating valve of a sound head and for operatively connecting the actuating means of the sound head to said movable member.

Still another object is to provide a sound head unit wherein the operative elements are combined, arranged and interconnected in a novel manner to render the unit compact, economical to make and assemble, and capable of reproducing sound with greater fidelity for a given volume than has heretofore been possible in sound amplifying units of like character.

A still further object is to provide novel means for housing the above parts whereby assembly, inspection, repair and adjustment are greatly facilitated.

Still another object is to provide a sound head of the air flow type with novel means for substantially eliminating resonant frequencies foreign to the frequency band being reproduced.

The above and further objects and novel features of the invention will more fully appear from the following detailed description when the same is read in connection with the accompanying drawings. It is to be expressly understood, however, that the drawings are for the purpose of illustration only and are not intended to define the limits of the invention, reference for this latter purpose being had primarily to the appended claims.

In the drawings, wherein like reference characters refer to like parts throughout the several views,

2

Fig. 1 is a sectional view taken in a vertical plane along a center line of a sound head embodying the present invention;

Fig. 2 is a transverse horizontal sectional view of the main housing of the sound head taken at the level indicated by section lines 2—2 of Fig. 1; and

Fig. 3 is an exploded perspective view of the movable grid and the mounting therefor.

Referring to Fig. 1, the novel sound head is illustrated as comprising a main housing 10 having a fluid chamber or passage 11 formed therein, said chamber being shaped in the form of a reversed and inverted L, with the lower end of the vertical portion thereof having a fluid inlet 12 and the horizontal portion having a discharge passage 13. The walls of inlet 12 are preferably threaded to receive the end of a suitable conduit connected to a source of expandible fluid at a pressure above atmospheric, as, for example, an air pump (not shown). A horn mount 14 is rigidly secured to housing 10 adjacent the end of discharge passage 13 and is adapted to constitute the throat portion of a suitable sound propagating device, such as an exponential horn (not shown), the latter being operatively secured to said mount, as by being threaded thereon at 15. Attached to the upper end of housing 10 and engaging horn mount 14 is a cup-shaped casing or cover plate 16 which forms a chamber 16a, the latter being adapted to receive the actuating mechanism of the sound head. A casing member 18 fixed to housing 10 below passage 13 provides a compartment 18a for suitable control means, said compartment communicating at the upper end thereof with the inlet portion of mount 14.

In order to impart sound producing characteristics to the air entering horn throat 14, novel valve means for modulating an air stream flowing therethrough are disposed between the end of passage 13 and said horn throat. As shown, said means comprise a stationary grid member 19 mounted on housing 10 across the open end of passage 13, said member having a plurality of vertical slots or ports 19a (Fig. 2) formed therein and being secured to said housing, for example, by screws 20. Pivotably mounted, in a novel manner to be more fully described hereafter, for cooperation with said stationary grid is a movable grid 21 (Figs. 1 and 3) constituted by a rectangular body portion provided with a plurality of vertical slots 21a, each of said slots being located opposite the solid areas between successive slots 19a of the stationary grid. To decrease the weight of grid 21 and the depth of

slots 21a, a plurality of vertical grooves are machined or otherwise formed in said grid, walls 21b of said grooves constituting reinforcing ribs for said grid. Depending from the lower end of grid 21 intermediate the side edges thereof is an arm or lug 22 and formed at the upper edge thereof is a lug 23 having a threaded recess 23a extending therethrough.

In order to mount grid 21 for pivotal movement about an axis perpendicular to slots 21a, a novel resilient cantilever support is provided which, in the form illustrated, comprises a relatively thin, plate-like member 24 formed from a resilient material, such as spring steel. Member 24 is rigidly secured to housing 10 below passage 13 (Fig. 1) by means, such as screws 25, in a plane substantially perpendicular to the face of grid 19 and has a portion thereof extending beyond the front face of said grid, said portion being provided with a central recess 26. Two arms 24a (Fig. 3) are thus formed in the free end of member 24 and are secured by screws 27 (Fig. 1) to the lower edge of grid 21 on opposite sides of lug 22, the latter projecting downwardly through recess 26 and being adapted for engagement with a balancing mechanism in a manner more fully described hereafter. Member 24 thus constitutes a cantilever suspension which normally tends to maintain the face of grid 21 in engagement with the face of grid 19 and to resiliently oppose any force tending to pivot grid 21 in a counterclockwise direction, as viewed in Fig. 1.

In order to vibrate grid 21 and modulate the air stream flowing through valve 19, 21, imparting sound producing characteristics thereto, an electromagnetic actuating mechanism 27, for example, of the magnetic type comprising an armature 28, is mounted in chamber 16a, said armature being vibrated in accordance with electric current undulations initiated by suitable means, such as the microphone of an amplifying unit (not shown). Armature 28 has the lower end thereof connected to one end of a grid driving link 29, the other end of said link being threaded into recess 23a of lug 23 so that vibrations of armature 28 are transmitted to grid 21 in a direction substantially perpendicular to the face of said grid producing a corresponding vibration of said grid about its pivotal axis.

It is preferable to have grid 19 formed so that it projects upwardly beyond the top surface of housing 10 and to have the upper edge portion of said grid engaging the inner face of mount 14, thereby providing a protective wall 30 between the interior of said mount and chamber 16a. An aperture 30a is provided in said wall for link 29 and the space between said link and the wall of said aperture is preferably filled with a ring or grommet 30b of suitable non-resonant, resilient material such as rubber. As a result, air leakage into chamber 16a, from the interior of horn mount 14, is substantially eliminated, preventing the admission of moisture into said chamber and avoiding any loss in efficiency of sound reproduction.

When air under pressure discharges from passage 13 through grid 19, a force is applied to grid 21, tending to pivot the latter in a counterclockwise direction, as viewed in Fig. 1. To partially counterbalance the effect of this force and establish an open equilibrium position for grid 21, pressure responsive balancing means are provided and connected in a novel manner to said grid. In the form illustrated, said means comprise a diaphragm 32 mounted in the vertical wall

portion of casing 10 beneath passage 13 so as to be subject to the difference between the pressure in air chamber 11 and the atmospheric pressure in compartment 18a, said diaphragm being held in fluid-tight engagement with a shoulder 33 in said casing by an annular member 34, which is, in turn, secured to said casing by screws 35. A pressure transmitting contact block 36 of suitable, non-resonant material, such as rubber, is mounted on diaphragm 32 and is connected to grid 21 by means of an arm 37 pivotably mounted at its lower end on the shank of a screw 38, the latter being threaded into casing 10. A recess 37a having convex walls is preferably provided in said arm to receive said screw shank thereby permitting pivotal movement of said arm about an axis perpendicular to the axis of said screw. Arm 37 has a screw 39 threaded therethrough at a point substantially opposite the center of diaphragm 32, block 36 being adapted to engage the end of said screw to actuate said arm in accordance with the air pressure in chamber 11.

Mounted at the upper end of arm 37 for transmitting pressure from the latter to grid 21 is a block 40 of non-resonant material, such as rubber, said block being of sufficient size to substantially fill the upper end of chamber 18a with one side thereof engaging lug 22 and the upper end thereof engaging member 24. Accordingly, in addition to transmitting forces from arm 37 to grid 21, block 40 acts to seal chamber 18a from the air stream passages and to dampen resonant frequencies which might otherwise be set up in member 24 and in the pressure transmitting linkage between the diaphragm block 36 and grid 21.

To prevent accumulation of moisture in horn mount 14 and between valve grids 19 and 21, a suitable drainage passage 41 is provided. As shown, said passage communicates at its upper end with substantially the lowest point on the interior of said horn mount and projects downward through said mount and cover 18, thereby eliminating the possibility of water accumulation at the horn mount and valve. The upper end of passage 41 is disposed opposite the lower end of lug 22 where substantially no air flow or current exists and, accordingly, said passage has a negligible effect on the amplitude and fidelity of the sound reproduction.

In order to heat grid valve 19, 21 and the air approaching said valve, heating means are mounted in a novel manner in the sound head, said means, as shown, comprising a pair of heating coils 42 (Fig. 2) extending vertically through housing 10 from the upper end thereof and located adjacent said valve on opposite sides of chamber 18a. Thus, the air entering chamber 11 is progressively heated as it approaches the grid valve and, in addition, the valve parts as well as the balancing mechanism and the connection between said mechanism and said parts are heated. Accordingly, precipitation of moisture due to the throttling action of the valve is minimized and the possibility of improper functioning of the movable parts of the sound head due to icing is eliminated.

In operation, air under pressure is admitted to chamber 11 through inlet 12 and acts to pivot grid 21 in a counterclockwise direction, as viewed in Fig. 1. This pivotal movement is opposed by cantilever 24 and by the balancing mechanism comprising diaphragm 32. The latter tends to move to the left with the admission of high pressure air into chamber 11 and by engaging the end of screw 39 to apply a force to arm 37, which

force pivots the latter in a counter-clockwise direction. This counter-clockwise torque is, in turn, transmitted through block 40 to lug 22, applying a clockwise torque to grid 21. The torques exerted by member 24 and the balancing mechanism on grid 21 increase in magnitude as the angular displacement of said grid increases so that at a predetermined angular position of said grid these torques set the latter in equilibrium.

Vibrations transmitted to grid 21 by armature 28 of actuating means 27 are thereafter accurately reproduced in said grid and are effective to impart sound producing characteristics to the air stream.

It is to be noted that the force transmitted to arm 37 by diaphragm 32 for a given pressure in chamber 11 depends on the axial position of screw 39 relative to said arm. Accordingly, screw 39 constitutes a simple and convenient means for adjusting the magnitude of the balancing force applied to grid 21 and serves to establish operative equilibrium or neutral position of grid 21. In the event the actuating mechanism for imparting vibrations to valve 19, 21 is of the dynamic type, screw 39 becomes the chief means for establishing a desired operative equilibrium position of valve member 21.

The efficiency and fidelity of sound reproduction in the above described unit, are greatly increased by minimizing the mass subject to the audio-frequency vibrations imparted by the actuating means to the valve. This is accomplished by providing the relatively short connecting link 29 as the only motion transmitting member between grid 21 and armature 28 and by the arrangement of the valve balancing means whereby screw 39 and balancing arm or beam 37 are isolated from diaphragm 34 and grid 21 by non-resonant members 36 and 40 which nevertheless act to transmit a balancing torque to said grid. The isolation of the balancing mechanism from the pressure responsive diaphragm practically obviates feed-back howls which are so difficult to control in conventional sound projecting devices. It is to be additionally noted that the balancing force, the force of the air stream, and the actuating force are applied to grid 21 substantially parallel to the plane of supporting plate 24 and in the direction of the free or supporting end of the latter. Accordingly, said plate is maintained under tension during operation and provides a pivot for grid 21 which insures substantially true arcuate movement of said grid during operation.

There is thus provided a novel sound head of the air flow type having a balanced modulating valve mounted and actuated in a novel manner so as to reproduce sound with great fidelity and volume. The weight of the parts adapted to vibrate with the movable valve member and the pressure responsive control diaphragm is maintained at a minimum so as to substantially eliminate feed-back howls and improve the fidelity of reproduction. The modulating valve and the actuating and balancing mechanisms therefor are arranged and combined in a novel manner to be readily and economically constructed and assembled, and to have the parts thereof available for ready inspection, repair and replacement. There is also provided novel means for pivotably mounting the movable member of a modulating valve whereby the latter moves in a true arc during operation, and means for insuring proper operation of said valve under adverse weather conditions.

Although only a single embodiment of the in-

vention is illustrated and described, it is to be expressly understood that the same is not limited thereto. For example, it will now be apparent to those skilled in the art that instead of the armature of a magnetic actuating unit, the voice coil of a dynamic unit may be connected to the modulating valve to actuate the latter. Moreover, a suitable resilient member of non-resonant material may be interposed between the lower end of arm 37 and housing 10 to maintain said arm against the head of screw 38. Various other changes may be made in the design and arrangement of parts without departing from the spirit and scope of the invention. For a definition of the limits of the invention, reference will be had primarily to the appended claims.

What is claimed is:

1. In a sound head of the type described, valve mechanism including a flat movable grid member, and a cantilever secured to one end of said member for pivotally mounting the same, actuating means for the grid member including a rod rigidly secured to said member, and means for balancing said member, said actuating means and said balancing means being so constructed and arranged as to apply forces to said member on opposite sides of said cantilever in a direction substantially parallel to the plane of said cantilever.
2. In an air head, means comprising a passage for a fluid stream, a grid valve for modulating said stream, said valve comprising a movable grid, a suspension plate secured as a cantilever to said means and having the free end thereof fixed to said grid to serve as a resilient hinge therefor, actuating means connected to the edge of said grid opposite the edge mounted on said plate, and balancing means for opposing the pivotal effect on said grid of the fluid stream, said balancing means comprising a pressure responsive member connected with said passage and the atmosphere, a pivotable link fulcrumed at the end thereof remote from said grid, a non-resonant member adapted to operatively connect said link to said grid and a second non-resonant member adapted to transmit forces from said pressure responsive member to said link, said first-named resonant member engaging said plate to dampen resonant vibrations thereof.
3. In a sound head wherein a fluid stream is modulated by a grid valve, means for balancing the movable grid of said valve comprising a pressure-responsive diaphragm adapted to produce a balancing force in accordance with the pressure of said stream, a force transmitting mechanism, a non-resonant member operatively connecting said mechanism to said diaphragm, and a second non-resonant member operatively connecting said mechanism to said movable grid, said mechanism including an adjustable member adapted to control the balancing force applied to said movable grid to thereby control the balanced position of said grid.
4. In a sound head wherein a fluid stream is modulated by a grid valve, means for balancing the movable grid of said valve comprising a pressure-responsive mechanism adapted to produce a balancing force in accordance with the pressure of said stream, a lever, an adjustable element mounted in said lever, a member of non-resonant material secured to said mechanism, said element engaging said member to transmit the balancing force from said mechanism to said lever, and a member of non-resonant material

mounted in said lever for applying the balancing force to said movable grid.

5. In a sound head having a grid valve, means for balancing the movable grid of said valve comprising a force transmitting lever, a pressure-responsive diaphragm for applying the balancing force, a non-resonant member connecting said diaphragm to said lever and a second non-resonant member connecting said lever to said movable grid to transmit the balancing force to the latter.

6. In a sound head wherein a fluid stream is modulated by a grid valve, means for balancing the movable grid of said valve comprising a diaphragm for producing a balancing force responsive to the pressure of said stream, a force transmitting member, a non-resonant member operatively connecting said force transmitting member to said diaphragm, and a second non-resonant member for connecting said force transmitting member to said movable grid.

7. In a sound head wherein a fluid stream is modulated by a grid valve including a movable grid, a plate-like cantilever support for pivotally mounting said grid with the slotted portion of said grid disposed on one side of said support in the fluid stream, said support being mounted to have its free end extending parallel to and in the direction of said fluid stream, and means for balancing said grid in said stream, said means being connected to said grid on the opposite side of said support from said slotted portion and applying a balancing force to said grid parallel to and in the direction of said stream.

8. In a sound head of the grid valve type, balancing means for the movable member of the grid valve comprising a diaphragm subjected to

the fluid pressure acting on said movable member, a lever for transmitting pressure from the diaphragm to said movable member, and non-resonant means operatively connecting said lever to said diaphragm and movable member.

9. In a sound head of the grid valve type, balancing means for the movable member of the grid valve comprising a diaphragm subjected to the fluid pressure acting on said movable member, a lever for transmitting pressure from the diaphragm to said movable member, non-resonant means operatively connecting said lever to said diaphragm and to the movable member, and means operatively connected to said lever for adjusting the neutral position of said movable member.
